Louis V. Lucia
ATTORNEY.

UNITED STATES PATENT OFFICE

2,328,253

LICENSE PLATE

Albert W. Becker, Hartford, Conn., assignor to
 Becker Permanent Plate Company, Hartford,
 Conn., a corporation of Connecticut

Application March 14, 1940, Serial No. 323,921

2 Claims. (Cl. 40—125)

This invention relates to number plates and more particularly to license plates as are used for indicating the registration number of automobiles and as further covered by my prior patent No. 2,110,119 issued March 1, 1938.

It has been found that it is considerably inconvenient to change the year insert plates which are used on the said registration plates, because, on a large number of automobiles, it requires the removal of the entire plate from the body of the vehicle before the insert, as shown in my above mentioned patent, can be removed and replaced.

On some vehicles, it is possible to change the inserts and reach in back of the plate to bend down the prongs of the insert without having to remove the entire plate. On the majority of the vehicles, however, the license plates are mounted so close to the body of the vehicle that they have to be removed from the vehicle before the year insert plate can be removed or renewed. This is particularly true in vehicles of the more modern designs where a special recess is provided in the body of the vehicle to receive and illuminate the license plate, and there is a positive tendency towards the adoption and standardization of the later model bodies.

An object of the present invention, therefore, is to provide a license number plate, of the character set forth in the above mentioned patent, in which the year insert number plate can be interchanged without necessitating the removal of the entire registration plate from the vehicle.

A further object of this invention is to provide means whereby the year insert plate may be assembled to the main or registration plate and locked in place thereon entirely from the front of the main plate.

A further object is to provide locking means operable entirely from the front of the main plate and means in connection with said locking means to visually indicate when the said locking means have been tampered with.

Further objects of the present invention will be clearly understood from the following description and from the accompanying drawing in which:

Fig. 1 is a front view of a registration number plate embodying my invention.

Fig. 2 is a view in central vertical section thereof on line 2—2 of Fig. 1.

Fig. 3 is an enlarged detailed view illustrating the elements of this invention.

Fig. 4 is a plan view in section on line 4—4 of Fig. 3.

Fig. 5 is an enlarged view illustrating a slightly modified form of the invention.

Fig. 6 is a plan view thereof.

Fig. 7 is a side view in vertical section on line 7—7 but showing an insert plate in place therein.

Fig. 8 is a view in elevation illustrating a further modified form of the invention.

Fig. 9 is a side view in vertical section on line 9—9 of Fig. 8.

10 As illustrated in the drawing the numeral 5 denotes the registration plate which may be of any desired size or design, having the usual insignia, in the form of letters 6, which may designate a certain district, numerals 7, designating the number of the vehicle, and letters 8 designating the state.

This invention contemplates the use of a panel 9 which may be preferably raised above the surface of the main plate and, if desired, the raised surface of this panel may be colored to match insignia of the main plate.

The said raised panel is provided with tabs, or retaining projections 10, which are spaced slightly above the surface of the raised panel so as to overlie an insert number plate 11 when inserted on the said raised panel and in back of the said projections.

As clearly illustrated in the drawing, the said projections may be formed above the surface of 30 the panel by piercing the main plate, as at 12, in order to simplify the operation of producing said projections.

The said panel may be provided with a raised border 13 which may be conveniently slotted, as 35 at 14, so as to provide a through recess as indicated on 15 to receive a tab 16 which projects from the insert plate 11.

When the said insert plate is to be assembled to the main plate, it is simply mounted upon the 40 surface of the raised panel and slid downwardly behind the projections 10 as clearly illustrated in Fig. 1. During this operation, the tab or tongue 16 is inserted through the openings 14 and then bent upwardly to lock the said insert by having the tab hooked over the bar which extends between the recesses 14.

The tab 16 may be provided with a weakening line, as indicated at 17 or the entire tab may be constructed of a sufficiently brittle metal which 50 will cause the tab to break off upon attempt to straighten the same so as to unlock it from the said number plate after the said tab has once been bent into place to lock said insert plate as illustrated in Fig. 1. This provides visual indication that the insert plate is lawfully being used

and that it has not been taken from another license plate, because if an attempt were made to remove the said year insert plate, the said tab would break off at the line 17 and so render it impossible to use the said insert plate upon another registration plate.

It will, therefore, be clearly seen that my invention will provide a substantial degree of security and protection against the unlawful removal or a year insert from the vehicle registration plates and that, when an attempt has been made to re-use said inserts, it will be clearly indicated by the absence of the tab bent over the locking portion or bar at the edge of the raised panel.

In the modified form illustrated in Fig. 8, the raised panel is omitted and the year insert 18 may be mounted upon the main plate 19 by the use of raised prongs 20. In this case the insert plate is slipped on the surface of the main plate, under the said ears, and the tab 21 is inserted through the yoke, or locking bar 22, and then bent over in the same manner as above described.

It will be also noted that the locking tabs, in each of the forms illustrated, are slightly to one side of the insert plate. This is to prevent the insertion of the plate in the wrong position.

In the form illustrated in Fig. 5, the raised border 22' on the panel is provided with extensions 23 in lieu of the tabs 10, and the sides of said border are tapered, together with the insert plate 24, so that when the said plate is inserted upon the panel any scratches caused by the projecting lips 23 will not show after the said plate is in place.

In this Fig. 5 there is also illustrated a modified form of a locking edge such as indicated at 26, which is provided by piercing the main plate, as at 21, so that the locking tab of the insert, if desired, may be bent backwardly through the said piercing and upwardly, around said edge 26, to lock the insert plate as clearly illustrated in Fig. 7 of the drawing. This latter form of locking means provides for securely holding the

insert plate in position, with the tab 16 in back of the main plate, and, at the same time, eliminating a tendency for tampering with the locking tab as when it is in the position illustrated in Fig. 1, although the said latter form is here preferred.

In this further modified form, apertures 28 and 29 are provided in the main plate and the insert, respectively, in order that a suitable member may be inserted, such as a nail or the like, therethrough to unbend the tab 16 for removal of the insert plate; the said tab being weakened on the line 30 so that it will break off to prevent re-use of the insert plate.

15 I claim:

1. A article of the character described comprising a main plate, a flat insert plate interchangeably mounted on said main plate and having a straight tab extending therefrom, means upon the front surface of said main plate providing an aperture adapted to receive said tab in its normal condition and permit bending of the tab entirely from a position at the front of said main plate to a position back of the same for locking said insert plate to said main plate, and means comprising apertures through said insert plate and main plate providing access to the bent tab for unbending the same to unlock the insert plate.

2. In an article of the character described a main plate, an auxiliary plate, and means for securing said auxiliary plate to the main plate; said means including a tab extending from the auxiliary plate, a tab receiving opening in said main plate adapted to receive said tab from a position in front of the main plate and permit bending of the tab to a position back of the main plate, and means including an aperture in said main plate adjacent to said tab receiving opening and a separate aperture in said auxiliary plate in register with the aperture in the main plate to provide access to said tab, when bent, and permit unbending thereof for releasing said auxiliary plate.
